US0D1064857S

(12) **United States Design Patent** (10) **Patent No.:** **US D1,064,857 S**
(45) **Date of Patent:** **** Mar. 4, 2025**

(54) **SENSING DEVICE**

(71) Applicant: **DCSTAR INC**, New York, NY (US)

(72) Inventor: **Ligui He**, New York, NY (US)

(73) Assignee: **DCSTAR INC**, New York, NY (US)

(**) Term: **15 Years**

(21) Appl. No.: **29/861,123**

(22) Filed: **Nov. 28, 2022**

(30) **Foreign Application Priority Data**

May 26, 2022 (CN) 202230317324.3

(51) **LOC (15) Cl.** **10-07**

(52) **U.S. Cl.**

USPC **D10/46**

(58) **Field of Classification Search**

USPC D10/46, 47, 49, 65, 83, 94, 96, 103,
D10/104.1, 104.2, 106.1; D14/358

CPC G06F 3/0304; G06F 3/042; G06F 3/016;
G01R 33/0094

See application file for complete search history.

(57) **CLAIM**

The ornamental design for a sensing device, as shown and described.

DESCRIPTION

FIG. 1 is a front view of a sensing device showing my new design;

FIG. 2 is a rear view thereof;

FIG. 3 is a left side view thereof;

FIG. 4 is a right side view thereof;

FIG. 5 is a top view thereof;

FIG. 6 is a bottom view thereof;

FIG. 7 is a front, top and right perspective view thereof; and,

FIG. 8 is a rear and right perspective view thereof.

1 Claim, 8 Drawing Sheets
